Primary Examiner — Ricky Pham

(57) **CLAIM**

The ornamental design for training chopsticks, as shown and described.

DESCRIPTION

FIG. 1 is a perspective view showing the front side, the top side, and the right side of my new design, training chopsticks, at the closed posture configuration, with the C-hook coupling bar mounted on the bottom chopstick connecting with the top chopstick via a circumferential groove carved into the top chopstick;

FIG. 2 is a perspective view showing the front side, the top side, and the left side thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof;

FIG. 9 is a perspective view showing the rear side, the top side, and the right side thereof;

FIG. 10 is a perspective view showing the rear side, the bottom side, and the right side thereof;

FIG. 11 is a perspective view showing the rear side, the top side, and the left side thereof;

FIG. 12 is a perspective view showing the rear side, the bottom side, and the left side thereof;

FIG. 13 is a perspective view showing the front side, the top side, and the right side, at another configuration, the open posture, of the training chopsticks;

FIG. 14 is a perspective view showing the front side, the top side, and the left side of the training chopsticks in FIG. 13;

FIG. 15 is a front view of the training chopsticks in FIG. 13;

FIG. 16 is a rear view of the training chopsticks in FIG. 13;

FIG. 17 is a top plan view of the training chopsticks in FIG. 13;

FIG. 18 is a bottom plan view of the training chopsticks in FIG. 13;

FIG. 19 is a left side view of the training chopsticks in FIG. 13;

(Continued)

FIG. 20 is a right side view of the training chopsticks in FIG. 13;

FIG. 21 is a perspective view showing the rear side, the top side, and the right side of the training chopsticks in FIG. 13; FIG. 22 is a perspective view showing the rear side, the bottom side, and the right side of the training chopsticks in FIG. 13;

FIG. 23 is a perspective view showing the rear side, the top side, and the left side of the training chopsticks in FIG. 13; FIG. 24 is a perspective view showing the rear side, the bottom side, and the left side of the training chopsticks in FIG. 13;

FIG. 25 is an exploded view of a portion of the training chopsticks, including the C-hook coupling bar, and the exposed circumferential groove carved into the top chopstick, in a perspective view showing the front side, the top side, and the right side;

FIG. 26 is a perspective view showing the front side, the top side, and the left side of the exploded portion in FIG. 25;

FIG. 27 is a perspective view showing the rear side, the top side, and the right side of the exploded portion in FIG. 25; FIG. 28 is a perspective view showing the rear side, the bottom side, and the right side of the exploded portion in FIG. 25;

FIG. 29 is a perspective view showing the rear side, the top side, and the left side of the exploded portion in FIG. 25;

FIG. 30 is a perspective view showing the rear side, the bottom side, and the left side of the exploded portion in FIG. 25;

FIG. 31 is a front view of the exposed circumferential groove carved into the top chopstick shown in the exploded view in FIG. 25;

FIG. 32 is a rear view of the exposed circumferential groove in FIG. 31;

FIG. 33 is a top plan view of the exposed circumferential groove in FIG. 31;

FIG. 34 is a bottom plan view of the exposed circumferential groove in FIG. 31;

FIG. 35 is a front view of the C-hook coupling bar shown in the exploded view in FIG. 25;

FIG. 36 is a rear view of the C-hook coupling bar in FIG. 35; FIG. 37 is a top plan view of the C-hook coupling bar in FIG. 35;

FIG. 38 is a bottom plan view of the C-hook coupling bar in FIG. 35;

FIG. 39 is a left side view of the C-hook coupling bar in FIG. 35; and,

FIG. 40 is a right side view of the C-hook coupling bar in FIG. 35.
